UNITED STATES PATENT OFFICE.

GEORGE W. WILLIAMS, OF CHICAGO, ILLINOIS, ASSIGNOR TO AARON WILLIAMS, OF SAME PLACE.

COPYING-PRESS.

SPECIFICATION forming part of Letters Patent No. 338,625, dated March 23, 1886.

Application filed September 10, 1884. Serial No. 142,550. (No model.)

To all whom it may concern:

Be it known that I, GEORGE W. WILLIAMS, of Chicago, county of Cook, and State of Illinois, have invented certain new and useful 5 Improvements in a Copying-Press, of which the following is a full, clear and exact description that will enable others to make and use the same, reference being had to the accompanying drawings, forming a part of this 10 specification.

This invention relates to an improvement on Letters Patent No. 301,418, granted to me July 1, 1884; and it consists of certain novel features in the construction, combination, and 15 operation of parts, as will be hereinafter more fully set forth and claimed.

Fig. 1 is a view in perspective of a copying press embodying my improvements, and Fig. 2 a side elevation and partial section of the 20 same.

Referring to the drawings, A represents the bed of the press; B, the arched bridge, and C the platen.

The longitudinal center of the arched bridge 25 B is provided with the vertical elongated chamber D, which is open at the lower end for the insertion of the spiral spring E and the vertical compressing-bolt F, inclosed therein. The bolt F passes up through the center of the 30 chamber D, and is encircled by said spring, as shown in Fig. 1.

The upper projecting end of the bolt F is threaded, while the lower or headed end is of a conical form, terminating with the enlarged flattened knob a, which bears on the center top of the platen, and has a swiveling engagement therewith. The annular shoulder a' on the bolt-head is of a sufficient diameter 35 to close the lower end of and form a movable bottom for the cylindrical chamber D, and at the same time provides a compressing-bolt, and a lever-handle having a threaded engagement with the upper end of said bolt, a' 40 of said chamber.

45 The platen C is provided with the curved lugs d d', which rise up on each side of the lower end of the bolt F, projecting over and engaging loosely with the upper side of the

knob, a, as shown in the drawings, thus detachably securing the platen and bolt in 50 proper relation to each other, and allowing the platen sufficient play to adjust itself and conform to the work.

The lever-handle G is provided with the threaded nut H, which is adapted to engage 55 with the upper correspondingly-threaded end of the bolt F. This nut has a bearing on top of the chamber D when the lever-handle G is turned down, which operating has the effect of drawing up the bolt, raising the 60 platen from the bed of the press, and compressing the spring in the chamber. Now, by turning the lever-handle upward and letting the same swing free on the bolt F, the spring E automatically imparts the required downward pressure to the platen. By this arrangement but little power is required to be applied to the lever-handle to compress the 65 spring and raise the platen, to insert or remove the copying matter. 70

It is of course obvious that different styles of springs may be used; and, if preferred, the spring and parts may be so arranged that the spring will expend its power in the opposite direction and raise the platen instead of forcing it down. 75

Having thus described my invention, what I claim, and desire to secure by Letters Patent, is—

In a copying-press, the combination, with a 80 bridge provided centrally with a chamber, of a spring inclosed in said chamber, an inverted screw-threaded bolt passing vertically through said chamber and provided with a shoulder forming a movable bearing for the 85 lower end of said spring, a platen provided on the upper side with curved lugs adapted to engage with the lower headed end of said bolt, and a lever-handle having a threaded engagement with the upper end of said bolt, 90 all combined and arranged to operate as and for the purpose set forth.

GEORGE W. WILLIAMS.
